UNITED STATES PATENT OFFICE

116,813

DESIGN FOR A MEASURING PUMP

William Dale Bost, Chicago, Ill., assignor to Orange Crush Company, Chicago, Ill., a corporation of Illinois

Application November 28, 1938, Serial No. 81,418

Term of patent 7 years

To all whom it may concern:

Be it known that I, William Dale Bost, a citizen of the United States and a resident of Chicago, in the county of Cook and State of Illinois, have invented a new, original, and ornamental Design for a Measuring Pump, of which the following is a specification, reference being had to the accompanying drawing, forming a part thereof.

Referring to the drawing:

Fig. 1 is an elevational view of a measuring pump showing my new design; and

Fig. 2 is a top plan view thereof.

I claim:

The ornamental design for a measuring pump, as shown.

W. DALE BOST.
